UNITED STATES PATENT OFFICE

2,095,201

DRINK VENDING MACHINE

Bert E. Mills, Oak Park, Ill., assignor to Mills Novelty Company, Chicago, Ill., a corporation of Illinois

Application July 15, 1933, Serial No. 680,613

12 Claims. (Cl. 225—21)

This invention relates to vending machines and more particularly to a machine for vending measured quantities of liquid such as orange drinks or other beverages.

An important object of the invention is to provide a machine of this character in which the quantity of liquid to be dispensed can be accurately controlled and can be readily varied by the proprietor of the machine to adapt the same to the sale of drinks of different value or to increase or decrease the quantity of the drink to be sold for a coin of a given denomination.

A further object of the invention is the provision of a machine of the type described in which provision is made for automatically positioning a cup to receive the drink just prior to the dispensing of the latter and for coordinating the positioning of the cup with the operation of a valve for controlling the drawing of a measured quantity of the liquid from a source of supply and for the discharging of the same into the cup.

Other objects and advantages of the invention will be apparent from the following detailed description, which, taken in connection with the accompanying drawings, discloses a preferred embodiment thereof.

Referring to the drawings:

Fig. 1 is a front elevation of a machine in which my invention is embodied;

Fig. 2 is an enlarged detail showing the valve mechanism and the connections between the valve and source of supply and the measuring chamber, this view also showing the breather tube by which the amount of the liquid to be dispensed on each operation of the machine may be controlled;

Fig. 3 is a sectional view taken substantially on the section line 3—3 in Fig. 1;

Fig. 4 is a sectional detail taken substantially along the line 4—4 in Fig. 3;

Fig. 5 is an elevational view of the coin control device and the timing mechanism for determining the time during which the measuring chamber is in communication with the source of supply upon each operation of the machine; and

Fig. 6 is a detail view of the timing mechanism. Upon said drawings the reference numeral 11 indicates a cabinet in the upper part of which there is positioned a liquid container 12 which is open at the top to receive the neck 13 of a bottle 14 which rests upon a resilient rim 15 provided at the mouth of the container 12 and

disposed in a central opening in a sloping top portion 16 of the cabinet 11.

The container 12 is communicably connected by a pipe 17 with a valve 18 contained in a housing 19 supported from the side of the cabinet, 5 said pipe being threaded into an opening 21 in the vertical wall of the container 12 near the bottom thereof and extending through the wall of the cabinet 11 upon which there is provided a boss 22 which is internally screw threaded to 10 receive a threaded projection 23 on the valve housing 19, said projection having an opening 24 therein in which an end of the pipe 17 is positioned. An inlet opening 25 leads from the opening 24 to the valve chamber.

Above the valve 18 is a measuring chamber or cup 26 supported in a base member 27 which is seated in the top of the valve housing 19 and has a central opening 28 communicating with the valve chamber.

A coin-operated mechanism for controlling the operation of the machine is mounted on the back of a plate 29 secured to the front of the cabinet 11. A coin slot 31 is provided in the plate and a rotatable operating lever or handle 32 protrudes from the front of said plate.

Upon insertion of a coin in said slot it enters a rotatable carrier (not shown) and, upon rotation of the handle 32, serves to turn a gear 33 shown in Fig. 5 of the drawings. The details of the coin actuating mechanism are not shown since they form no part of the present invention. They are fully illustrated in Patent No. 1,869,616 granted Aug. 2, 1932 on an application of Bruno Radtke, which patent is owned 35 by the applicant's assignee.

Rotation of the gear 33 causes one of two pins 34, 34' thereon, acting upon a cam portion 35 of a lever 36 to turn said lever in counterclockwise direction on its pivot 37 (see Figs. 3 and 4). 40 The lower end of said lever carries a pin 38 extending through a slot 39 in the casing and connecting with a bar 41 extending through a channel 42 cast in the boss 22, said bar connecting at its opposite end with a lever 43 which is 45 pivoted at 44 to the frame and is adapted to actuate an arm 45 of a cup tripping mechanism indicated generally at 46 in Fig. 3 of the drawings. This mechanism is of known construction and is not illustrated in detail, it being noted merely 50 that it consists of a series of slides 47 adapted to support a stack of cups 48 in a chute 49 and being operable upon each actuation of the lever 43 to release one cup and engage beneath the next succeeding one, the released cup being directed 55

down an inclined guideway 51 to a holder 52 beneath the valve housing 19.

The gear 33 meshes with a smaller gear 53 (see Fig. 5) which is mounted on the rear side of the plate 29 and carries a pin 54 positioned eccentrically thereon. Upon rotation of said gears said pin 54 engages a cam 55 which is pivoted at 56 to the frame and forces the same downwardly, thereby actuating a bar 57 which is connected at one end to the end of said cam and at the other end to a lever 58 which serves to turn the gears of a clock mechanism mounted between the plate 29 and a plate 59 supported from said plate 29 by posts 61. This action is accomplished by means of a pawl 62 pivotally mounted on the lever 58 and held by a flat spring 63 in engagement with a ratchet wheel 64 mounted on a shaft 65 which also supports the lever 58 and a gear 66 forming a part of the clock mechanism.

20 The cam member 55 has a cam 67 formed thereon near its pivoted end, which cam engages a tail part 68 on a locking lever 69 which is pivoted at 71 to the frame. Upon downward movement of the member 55 said locking lever is permitted to rise under the influence of a spring 72 connected at one end to a hook 73 on the upper side of said lever and at the other end to a lug 74 on the frame. Meantime one of the pins 34 or 34' has moved against a lever 75 having an arcuate cam portion 76 engageable by said pin, said lever being thereby moved downwardly, turning on its pivot 77 against the tension of a spring 78 connected at one end to a tail part 79 on said lever and at the other end to a lug 81 on the frame. Said lever 75 has a tooth 82 on its underside adapted to be engaged by a lateral projection 83 on the lever 69 when said lever 75 has been moved downwardly to the lower end of its stroke. Said projection 83 has ratchet teeth 84 thereon cooperating with said tooth 82 to prevent release of the lever 75 until the lever 69 has again been moved downwardly in manner which will presently be described.

The upper end of the arm 75 is connected with a bar 85 which, at its opposite end, connects with a crank 86 on a shaft 87 (see Fig. 3) which is rotated against the tension of a spring 90 mounted thereon and operates the valve 18, turning the same clockwise a quarter turn from the position shown in Fig. 2, thereby causing a passageway 88 to be brought into registration with the inlet opening 24 in the valve casing 19 and causing a passageway 89 in said valve head to register with the opening 28 in the base member of the measuring cup 26. Communication is thus established between the container 12 and said cup and the cup is filled to a predetermined point, the liquid being forced through the pipe 17 by the head pressure in said container 12.

60 For the purpose of accurately controlling the amount of liquid admitted to the measuring cup 26 I provide a breather tube 91 extending through a cover member 92 on said cup and having an air tight fit therewith provided by a packing gland 93. Said tube has a very small passageway 94 therein so that the liquid entering the tube to seek the level in the container 12 will be of such small quantity as not to appreciably affect the volume of the drink delivered into the cup 48. The lower end of said breather tube 91 may be so positioned as to determine the liquid level in the cup 26 and may be readily varied by the proprietor of the machine to vary the size of the drink to be dispensed upon each operation of the machine.

It will be recalled that prior to the turning of the valve 18 to establish communication between the container 12 and measuring cup 26 the gears of the clock mechanism have been turned by the downward movement of the cam member 55 acting upon the bar 57 and lever 58. When the pin 54 on the gear 53 has passed beyond said cam member 55 the latter is drawn upwardly by means of a spring 95 connected at one end to a lug 96 on said member and at the other end to the lug 74 on the frame. This movement, however, is retarded and the time thereof determined by a pendulum 97 depending from a member 98 pivoted on one of the posts 61 and carrying a pin 99 movable into and out of engagement with a toothed wheel 101 as the pendulum swings, said wheel being mounted on a shaft 102 carrying a pinion 103 meshing with the gear 66.

As the member 55 approaches its upper position the cam 67 thereon, acting on the tail part 68 on the lever 69, forces the latter downwardly against the tension of the spring 72 thereby releasing the lever 75 which is raised by the action of the spring 78, a cushioned stop 104 being provided on the frame above said lever to limit the upward movement thereof. In returning to its upper position said lever 75 raises the bar 85 thereby turning the shaft 87 to move the valve 18 to the position shown in Fig. 2 of the drawings, in which position the liquid in the measuring cup 26 is allowed to pass through the passageway 88 in the valve head and through an outlet opening 105 in the casing 18 into the cup 48, which has been previously positioned to receive the drink, as above described. The valve 18 then remains in this position until another coin is inserted and the handle 32 again operated when the cycle of operations just described is repeated.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What I regard as new and desire to secure by Letters Patent is:

1. A drink vending machine comprising a source of supply of drinking cups, a source of supply of the drink, a normally-empty drink measuring receptacle having an opening in the lower end thereof through which the drink may be drained, a breather tube adjustably supported in the top of said receptacle and extending downwardly therein to a point in the plane of the desired liquid level in said receptacle, a valve housing having passages connecting with the source of supply and said opening in the measuring receptacle, a valve in said housing, and mechanical means operable through a single manual operation to successively transfer a cup from said source of cup supply to a position to receive the drink, and to operate said valve to discharge the drink from the measuring device into said cup.

2. A drink vending machine comprising a source of supply of drinking cups, a source of supply of the drink, a normally-empty drink measuring receptacle having an opening in the lower end thereof through which the drink may be drained, a breather tube adjustably supported in the top of said receptacle and extending downwardly therein to a point in the plane of the desired

liquid level in said receptacle, a valve housing having passages connecting with the source of supply and said opening in the measuring receptacle, a valve in said housing, and mechanical means operable through a single manual operation for transferring a cup from said source of cup supply to a position to receive said drink and for thereafter opening said measuring receptacle to communication with said source of supply 5 of the drink and for discharging the measured drink from said receptacle to the positioned cup.

3. A drink vending machine comprising a source of supply of drinking cups, a source of supply of the drink, a drink measuring receptacle 10 having an opening in the lower end thereof through which the drink may be drained, a breather tube adjustably supported in the top of said receptacle and extending downwardly therein to a point in the plane of the desired liquid level in said receptacle, a valve housing 15 having passages connecting with the source of supply and said opening in the measuring receptacle, a valve in said housing, and mechanical means operable through a single manual operation for transferring a cup from said source of cup supply to a position to receive said drink and for thereafter opening said measuring receptacle to communication with said source of supply 20 of the drink and timing mechanism for controlling the period of time during which said measuring receptacle is open to communication with said source of supply of the drink.

4. A drink vending machine comprising a source of supply of drinking cups, including a cup dispensing device, a source of supply of the drink, a drink measuring receptacle, a valve for communicably connecting said receptacle with said source of supply of the drink, and mechanical means for transferring a cup from said source of cup supply to a position to receive the drink and for operating said valve to first open said measuring receptacle to communication with said source of drink supply for a predetermined period and for thereafter discharging the drink from said 45 receptacle to the positioned cup, said means including a manually rotatable shaft, means operatively connecting said shaft with the cup dispensing device, and additional means providing operative connection between said shaft and the 50 valve.

5. A drink vending machine comprising a container for holding a supply of the drink, a measuring device including a cup having an opening in the lower end thereof from which the drink may be drained, means including a valve for connecting the container with said opening in the cup to enable the latter to be filled by head pressure on the liquid in the container, means for controlling the level of the liquid admitted to the measuring cup and maintaining it at a predetermined point below the top of the cup regardless of a higher liquid level in the container, and mechanical means including a manually rotatable shaft operatively connected with said valve for opening 60 said receptacle to communication with said container and for thereafter discharging the contents of the measuring cup into a drinking cup positioned to receive the same.

6. A drink vending machine comprising a container for holding a supply of the drink, a liquid measuring device including a cup adapted to be communicably connected with said container, a breather tube extending into said cup from the top to a point in the plane of the desired liquid 75 level in said cup, said tube having a small opening

therein in which the liquid may seek the level of the liquid in said container without appreciably adding to the volume of the liquid in said cup, a valve for opening said measuring cup to communication with said container and mechanical 5 means for causing operation of said valve after a measured time interval to discharge the contents of said measuring cup into a drinking cup positioned to receive the same.

7. A drink vending machine comprising, in combination, a source of supply of drinking cups, including a cup dispensing device, a drink storage reservoir provided with a draw-off pipe, a normally empty drink measuring receptacle having an opening in the lower end thereof, a breather tube extending into said receptacle from the top to a point in the plane of the desired liquid level in said receptacle, a valve housing having a discharge passage therein and additional passages therein connecting with said draw-off pipe 20 and said opening in the measuring receptacle, a valve in said housing adapted in one position to connect said draw-off pipe with the measuring receptacle and in the other position to connect the latter with the discharge passage in said 25 housing, and means including an actuating member operable through a single manual operation for transferring a cup from the source of cup supply to a position to receive the drink, and to operate said valve to discharge the measured 30 drink from said receptacle into said cup, said means including a manually rotatable shaft, means operatively connecting said shaft with the cup dispensing device, and additional means providing operative connection between said shaft 35 and the valve.

8. A drink vending machine comprising, in combination, a source of supply of drinking cups, including a cup dispensing device, a drink storage reservoir provided with a draw-off pipe, a normally empty drink measuring receptacle having an opening in the lower end thereof, a breather tube extending into said receptacle from the top to a point in the plane of the desired liquid level in said receptacle, said tube having a small 40 opening therein in which the liquid may seek the level of the liquid in said container without appreciably adding to the volume of the liquid in said receptacle, a valve housing having a discharge passage therein and additional 45 passages therein connecting with said draw-off pipe and said opening in the measuring receptacle, a valve in said housing adapted in one position to connect said draw-off pipe with the measuring receptacle and in the other position to connect the latter with the discharge passage in said 50 housing, and means including an actuating member operable through a single manual operation for transferring a cup from the source of cup supply to a position to receive the drink, and to operate said valve to discharge the measured 55 drink from said receptacle into said cup, said means including a manually rotatable shaft, means operatively connecting said shaft with the cup dispensing device, and additional means providing operative connection between said shaft 60 and the valve.

9. A drink vending machine comprising, in combination, a source of supply of drinking cups, including a cup dispensing device, a drink storage reservoir provided with a draw-off pipe, a normally empty drink measuring receptacle having an opening in the lower end thereof, a breather tube extending into said receptacle from the top to a point in the plane of the desired liquid 75 level in said cup, said tube having a small opening

- sired liquid level in said receptacle, a valve housing having a discharge passage therein and additional passages therein connecting with said draw-off pipe and said opening in the measuring 5
5 receptacle, a valve in said housing adapted in one position to connect said draw-off pipe with the measuring receptacle and in the other position to connect the latter with the discharge passage in said housing, and means including an 10
10 actuating member operable through a single manual operation for transferring a cup from the source of cup supply to a position to receive the drink and for operating said valve to first establish connection between the storage reser- 15
15 voir and the measuring receptacle and to there-
after discharge the measured drink from said receptacle to the positioned cup, said means including a manually rotatable shaft, means opera-
tively connecting said shaft with the cup dis- 20
20 pensing device, and additional means providing operative connection between said shaft and the valve.
10. A drink vending machine comprising, in combination, a source of supply of drinking 25
25 cups, including a cup dispensing device, a drink storage reservoir provided with a draw-off pipe, a normally empty drink measuring receptacle having an opening in the lower end thereof, a breather tube extending into said receptacle 30
30 from the top to a point in the plane of the desired liquid level in said receptacle, a valve housing having a discharge passage therein and additional passages therein connecting with said draw-off pipe and said opening in the measuring 35
35 receptacle, a valve in said housing adapted in one position to connect said draw-off pipe with the measuring receptacle and in the other position to connect the latter with the discharge passage in said housing, and means including an 40
40 actuating member operable through a single manual operation for transferring a cup from the source of cup supply to a position to receive the drink and for operating said valve to first establish connection between the storage 45
45 reservoir and the measuring receptacle and to thereafter, after a measured time interval, discharge the measured drink from said receptacle to the positioned cup, said means including a manually rotatable shaft, means operatively connecting said shaft with the cup dispensing device, and additional means providing operative 50
50 connection between said shaft and the valve.
11. A drink vending machine comprising, in combination, a main supply receptacle, a normally empty measuring cup, a faucet communicating with said cup, a valve adapted in one position to establish communication between said

measuring cup and main source of supply, and in another position to close said line of communication and establish communication between the measuring cup and an outlet passage in the faucet, a source of supply of drinking cups, a cup holder beneath said faucet, a device for discharging individual cups from said source of supply into said cup holder, and operating mechanism including an actuating member, means operable thereby for turning said valve 10 to establish communication between the measuring cup and the source of supply, means also operable by said actuating member for operating said cup discharge device to position one of said individual cups beneath the faucet, and means 15 including a timing device for returning said valve to its original position after a predetermined time to thereby close communication between the measuring cup and the main source of supply and establish communication between said 20 measuring cup and the positioned drinking cup to permit the contents of said measuring cup to discharge into the drinking cup.

12. A drink vending machine comprising, in combination, a main supply receptacle, a nor- 25 mally empty measuring cup, a faucet communi-
cating with said cup, a valve adapted in one position to establish communication between said measuring cup and main source of supply, and in another position to close said line of com- 30
munication and establish communication be-
tween the measuring cup and an outlet passage in the faucet, a source of supply of drinking cups, a cup holder beneath said faucet, a device for discharging individual cups from said source of 35
supply into said cup holder, and operating mech-
anism including an actuating member, means operable thereby for turning said valve to es-
tablish communication between the measuring cup and the source of supply, means also operable 40
40 by said actuating member for operating said cup discharge device to position one of said in-
dividual cups beneath the faucet, means for main-
taining back atmospheric pressure in the 45
measuring cup to limit the extent to which the 45
cup can fill while in communication with said source of supply, and means including a timing device for returning said valve to its original position after a predetermined time to thereby close communication between the measuring cup 50
50 and the main source of supply and establish communication between said measuring cup and the positioned drinking cup to permit the contents of said measuring cup to discharge into the drinking cup.

BERT E. MILLS.
